UNITED STATES PATENT OFFICE.

FEODOR KOVALSKI, OF WEST LYNN, MASSACHUSETTS.

PADLOCK.

1,252,815.

Specification of Letters Patent.

Patented Jan. 8, 1918.

Application filed July 16, 1917. Serial No. 180,841.

To all whom it may concern:

Be it known that I, FEODOR KOVALSKI, a citizen of Russia, residing at West Lynn, in the county of Essex and State of Massachusetts, have invented certain new and useful Improvements in Padlocks, of which the following is a specification.

This invention relates to new and useful improvements in padlocks.

10 The primary object of the invention is the provision of a key-operated padlock so arranged that a person unfamiliar with its manner of operation will have great difficulty in manipulating the lock mechanism while the same is readily locked and unlocked by any authorized person provided with the proper key.

20 A further object of the device is the provision of a padlock arranged with the shackle releasing means normally guarded by a device which is only operable in a certain peculiar manner and whereby the lock possesses great security against being opened by unauthorized persons.

25 A still further object of the device is the provision of a padlock having a shackle release and a guard therefor, both of which are adapted for separate and successive actuations by a single key, the entire structure 30 possessing great strength and security.

In the drawings forming a part of this application and in which like designating characters refer to corresponding parts throughout the several views,

35 Figure 1 is a front elevation of the device in its normally locked arrangement,

Fig. 2 is a similar view with the guard plate shifted for permitting the release of the lock mechanism.

40 Fig. 3 is a view similar to Fig. 1 with the guard and cover plates removed.

Fig. 4 is a view similar to Fig. 2 with the guard and cover plates removed and showing the key in section positioned as 45 having released the shackle,

Fig. 5 is a view similar to Fig. 3 showing the key in section and in position as having released the guard plate.

Fig. 6 is a substantially central sectional view taken through the device with the

mechanism in its normally locked arrangement.

Fig. 7 is a view partly in side elevation and partly in section similar to that shown in Fig. 6 and with the key inserted for releasing the guard plate. 55

Fig. 8 is a view similar to Fig. 7 with the guard plate mechanism released.

Fig. 9 is a similar sectional view looking in the opposite direction from that shown in Fig. 6. 60

Fig. 10 is a plan view of the underside of the guard plate.

Fig. 11 is a perspective view of the upper side of the cover plate. 65

Fig. 12 is a perspective view of the mechanism mounting plate.

Fig. 13 is a perspective view of the shackle bolt and its releasing lever.

Fig. 14 is a perspective view of the guard 70 plate latch and spring.

Fig. 15 is a perspective view of the spring catch employed with the guard plate mechanism.

Fig. 16 is a perspective view of a portion 75 of the mounting plate and the releasing cam for the latch.

Fig. 17 is a detail sectional view taken through the cam and the adjacent portion of the mounting plate and the back plate 80 of the lock and

Fig. 18 is a perspective view of the key employed with the device.

Referring more in detail to the drawings a padlock casing 10 of the usual substantial circular form is provided having a back plate 11 and a forwardly positioned cover plate 12, the latter being removably secured upon the casing 10 by suitable screws 13 extending through perforations 14 in the plate 12 and threaded into side lugs 15 arranged within the casing. The side wall 16 of the casing 10 has one flat side 17 with a swinging shackle 18 pivoted as at 19 adjacent one end thereof and between 95 the base plate 11 and cover plate 12 while the casing end 17 is provided with a receiving opening 20 adjacent its opposite end adapted for the reception of the terminal loop 21 of the shackle, the said loop pro- 100

jecting inwardly of the casing 10 when the shackle is closed.

A mounting plate 22 adapted for positioning the lock mechanism within the casing 10 is arranged therein having feet 23 raising upon the back plate 11 for spacing the plate 22 from the back plate while peripheral notches 24 are arranged in the plate 22 for accommodating the aforementioned lugs 15.

10 Parallel upstanding ears 25 are struck out of the plate 22 having guide openings 26 therethrough adapted for the sliding reception of the shackle bolt 27 while a leaf spring 28 having one end anchored to an 15 upstanding post 29 carried by the plate 22 engages the adjacent end of the bolt 27 for normally maintaining the latter projected in its securing position inwardly of the aforementioned casing end opening 20 with 20 the bolt 27 extending through the loop 21 of the shackle 18 when the latter is closed.

A guard plate 30 of substantially the same form and dimensions as the cover plate 12 is flatly arranged for rotation upon the 25 latter by being centrally pivoted thereto by a rivet 31, the said guard plate having a central key hole slot 32 adapted to be brought into register with either one of two similar key hole slots 33 and 34 provided 30 through the cover plate 12. A retaining latch 35 is provided for the guard plate 30 being pivoted as at 36 to a post 37 carried by the mounting plate 22, an upstanding finger 38 being arranged at one end of the 35 latch adapted for normally positioning within the perforation 39 of the cover plate 12 and for locking engagement within a keeper socket 40 in the lower side of the guard plate 30 when such socket is brought 40 into alinement with the perforation 39. A leaf spring 41 secured to the cover plate 12 engages the end 42 of the latch 35 at a point opposite the finger 38 for normally pressing the said finger in a direction toward the 45 guard plate 30.

A circular disk form of cam 43 is arranged with a hub 44 journaled in the mounting plate 22 with a key post 45 positioned centrally beneath the key hole slot 33 of 50 the cover plate 12. A retaining catch 46 is arranged beneath the plate 22 being pivoted as at 47 to an extension 48 of one of the ears 25, an upstanding tooth 49 being provided upon the catch 46 at its free end 55 normally maintained within a perforation 50 of the mounting plate 22 by means of a spring 51 carried by the catch and engaging the back plate 11 of the casing. The cam 43 is so positioned beneath the latch 35 as 60 to bring the arcuate side flange 52 thereof into elevating engagement with either the securing ledge 53 or the releasing ledge 54 of the latch during the revolution of the cam disk 43, it being noted that the ledges

53 and 54 are arranged at opposite sides of 65 the pivot 36 of the latch 35 with the ledge 53 arranged adjacent the locking finger 38. An opening 55 is provided through the disk 43 adapted for receiving the catch tooth 49 when the opening 55 is in alinement with 70 the mounting plate perforation 50 and which occurs when the flange 52 is beneath the latch ledge 53 with the finger 38 of the latch extending through the perforation 39 of the cover plate 12 and into the keeper 75 socket 40 of the guard plate 30. It will be understood that the arrangement just described occurs when the lock is in its normally secured arrangement with the key 80 hole slots 32 and 33 in alinement with each other and at which times the cutaway sides 56 and 57 of the plates 30 and 12 respectively are in alinement with each other as well as with the similar cutaway side portion 58 of the back plate 11 and being adjacent the flat end 17 of the casing wall 16.

A key 59 is provided for the lock adapted for insertion through the slot 32 of the guard plate 30 and for arrangement within the cover plates slot 33 when it is desired to release the guard plate 30 by manipulating the latch 35 while the key 59 is arranged through the cover plate slot 34 after the guard plate has been released and shifted for bringing the slots 32 and 34 into register for the accommodation of the key for the purpose of retracting the bolt 27 to release the shackle 18. With slots 32 and 33 in register as arranged when the lock is in its normal condition, the key 59 will be inserted through the side slots with the central bore 60 of the key arranged upon the post 45. By turning the key 59, the depending toe 61 of the bit 62 of the key may be positioned through the opening 55 of the cam disk 43 for engaging the catch tooth 49. By pushing inwardly upon the key 59 when in such position, the catch 46 will be depressed against the action of the spring 51 and the tooth 49 being released from the cam 110 43, a turning of the key 59 will shift the flange 52 from beneath the latch ledge 53 to a point beneath the ledge 54 thereof and which movement will depress the finger 38 withdrawing the same from the socket 40 115 of the guard plate 30. Upon removing the key 59, the flange 52 will maintain the latch 35 released permitting the guard plate 30 to be turned upon its pivot 31 so as to bring the slot 32 with the guard plate in register 120 with the slot 34 of the cover plate 12. The key 59 may then be inserted through the slots 32 and 34 with the bore 60 of the key receiving the key post 62' of the mounting plate 22.

A releasing lever 63 is pivoted as at 64 substantially centrally on the bolt 27, a spring 65 being arranged between the said

bolt and lever for normally maintaining the lever extended in a direction toward the key post 62'. With the key mounted upon the post 62' and turned clockwise as shown in Fig. 3 of the drawing, the key ward 62 will engage the lever 63 swinging the same toward the casing opening 22 and permitting the edge 66 of the bit 62 to rest within the groove 67 at the front end of the lever 63 as indicated by dotted lines in said figure. A reversal of the movement of the key will then force the lever 63 in the direction of the shackle hinge 19 sliding the bolt 27 therewith and releasing the same from the loop 21 as above illustrated in Fig. 4 of the drawing. It will be evident that the shackle 18 may then be swung outwardly while upon removing the key 59 from its engagement with the lever 63, the spring 28 will again project the bolt 27. The key 59 may be readily withdrawn from the lock when desired and by again shifting the plate 30 the key may be positioned upon the post 45 for returning the disk 43 to its position for reengaging the latch 35 with the plate 30. It will be obvious that the bolt 27 is normally projected when the key is out of the lock while at such times the shackle 18 may be engaged by the bolt or not as found desirable, while the disk 43 may be readily shifted by the key for either locking or releasing the guard plate 30.

A padlock is provided requiring only one key and so constructed that a person unfamiliar with the manner of operating the mechanism by means of the key will be unable to retract the bolt 27 and release the shackle 18 without great difficulty regardless of which one of the cover plate slots 33 or 34 is accessible through the guard plate slot 32. It will also be seen that the key 58 may be completely revolved in either direction when positioned upon the post 62', the ward 62 of the key being adapted to hit the lever 63 and move the same aside, permitting the key to revolve. It will be noted that extreme care must be taken in turning the key 59 for the purpose of retracting the bolt 27 in seating the ward end 62 within the lever groove 67 when the ward and lever are positioned in angular relation. This

lock may be employed wherever it is found desirable to arrange a padlock for insuring great security.

What I claim as new is:—

55

1. A padlock comprising a casing, a locking bolt arranged therein, a cover plate for said casing having two key hole slots therein, a guard plate superposed on said cover plate, one of the said slots being adapted for the reception of a key for actuating the said bolt, a locking latch for said guard plate, a shifting cam for said latch revolvably arranged within said casing, a post upon said cam normally positioned in alignment with the other one of said cover plate slots and a key releasable spring catch for the said cam arranged adjacent the cam.

60

2. A padlock comprising a casing, a shackle upon said casing, a locking bolt for the shackle, a cover plate for the casing having a slot adapted for the reception of an operating key for said bolt, the said cover plate provided with a second slot adapted for the reception of a releasing key for said latch, and a guard plate for said slots pivoted upon the cover plate and arranged with a key receiving slot adapted to register with either of the slots of said cover plate selectively, and a latch within the casing controlling the movement of the guard plate.

65

3. A lock comprising a casing, a sliding bolt within the casing, a cover plate for the casing having a key receiving slot adjacent said bolt, a guard plate revolvably mounted upon said cover plate having a slot therein adapted to register with the slot of the cover plate, a retaining latch for said guard plate arranged within the casing, a controlling cam for said latch journaled within the casing, a spring catch for the cam arranged adjacent the latter, a key adapted for releasing the said catch and operating the said cam, the said cover plate being provided with a second slot adapted to register with the slot of the guard plate and arranged outwardly of said cam adapted for the reception of said key.
